UNITED STATES PATENT OFFICE

2,672,338

PYLON MOUNTED TOY AIRPLANE
ROUNDABOUT

Melvin H. Freedman, New London, Conn.

Application September 18, 1952, Serial No. 310,197

6 Claims. (Cl. 272—31)

1

The present invention relates to toys and more particularly relates to a flight control apparatus for model airplanes.

A primary object of the invention is to provide a toy flight control apparatus for model airplanes that will cause a model airplane attached thereto to fly upwardly in eccentric circles to simulate the flight of an airplane around a racing pylon.

A further object of the invention, ancillary to the preceding object, is to provide a toy flight control apparatus of the above-described character that consists of a simulated racing pylon with a ring disposed thereon with means for attaching the pylon to a supporting surface and means for preventing the ring from flying off the pylon as the same is revolved upwardly on the pylon through the flight of a controlled model airplane.

A still further object of the present invention is to provide a toy flight control apparatus that may be used equally outdoors or indoors and which is of "knockdown" construction whereby the same may be packaged flat and assembled by the user.

These, together with various ancillary objects and features of the invention which will later become apparent as the following description proceeds, are attained by the present invention, a preferred embodiment of which is shown by way of example only in the accompanying drawings, wherein:

Figure 1 is a perspective view of the toy flight control apparatus in operation;

Figure 2 is a side elevational view in cross-section of the pylon and ring comprising the control apparatus;

Figure 3 is a side elevational view, in operation, of the flight control apparatus of modified construction;

Figure 4 is a top view taken substantially along section line 4—4 in cross-section of the control apparatus; and

Figure 5 is a side elevational view, with parts being cut-away of a suitable model airplane to be utilized with the flight control apparatus.

Referring now to the accompanying drawings in detail, it will be noted that like reference characters are utilized throughout the various views to designate similar parts.

The toy flight control apparatus is designated in its entirety by the numeral 10 and comprises generally a simulated racing pylon 12, which may be constructed of any suitable material such as cardboard, plastic, wood or metal and a tubular ring 14 which also may be constructed of any suitable material, being preferably of plastic.

The pylon 12 is in the shape of a four-sided,

2

truncated pyramid in the preferred embodiment shown. It is to be understood, however, that the same may be conical or triangular or of any other suitable configuration. The pylon 12 is preferably formed from a single sheet or blank of material with the edges meeting at one corner thereof and fastened in any suitable manner as shown at 16 in Figure 4.

At the corners of the base of the pylon 12, horizontally extending flat tabs 18 are secured having apertures 20 therein for the reception of headed fasteners, such as pins or the like, for securely anchoring the pylon to a supporting surface, such as a floor or rug, indicated by the numeral 22.

Referring particularly to Figure 2, pins 24 are shown anchoring the tabs 18 to a supporting surface while a suitable mucilage or mucilaginous film 26 is shown attaching the mating edges of the pylon to one another.

At the top of the pylon 12, two of the opposite side edges thereof are folded on one another as indicated at 28 to form a closed top for the pylon. Through this closed top 28 is an aperture 30 receiving a suitable headed fastener 32 which fastener in turn secures the retaining lid or disc 34 to the top of the pylon.

As will be noted from Figures 2 and 4, when the ring 14 is at rest, the same seats frictionally against the corner edges of the pylon a short distance above the base of the pylon. A U-shaped staple or eye member 36 is secured to the outer surface of the ring 14 and one end of a suitable thread, string, wire or the like 38 is secured thereto. The other end of the thread 38 is secured to the wing tip of a wheeled, self-propelled model airplane indicated generally by the numeral 40.

Referring to Figure 5, a suitable type model airplane 40 is shown having a hollow fuselage 42 with a rubber band motor 44 therein for rotating the propeller 46 to propel the airplane in flight. It is to be understood, however, that other type model aircraft such as rocketships, "stick" type rubber powered or gasoline motor propelled model airplanes could be used with the invention and the invention is not limited to any particular type aircraft.

In operation, the rubber powered toy airplane, or other miniature aircraft, is secured at its wing tip to the ring 14 by means of the thread 38. As the plane takes off around the pylon 12, the plastic ring 14 will also rise up in eccentric circles which appear to be gradually widening as the ring rides up the pylon until the ring reaches the top of the pylon and engages the retaining lid 34.

to prevent the plane from flying free. Obviously, this arrangement provides or permits indoor power flying with no damage to household valuables while also providing the aforementioned eccentric motion to the airplane's flight which simulates the flight of airplanes around a racing pylon. As shown in the preferred embodiment, pins 24 secure the pylon against wobbling or toppling while the same is being utilized for controlling the flight of a model airplane. The pylon 12 may be suitably decorated in black and white squares or other colored squares as indicated at 48.

In the modification shown in Figure 3, the flight control apparatus 10 is substantially identical to the ones shown in Figures 1, 2 and 4. However, in the modification of Figure 3, two rings are shown, the second ring being designated by the numeral 50, whereby a plurality of model airplanes may be flown at the same time. In this connection, it might be further noted that a plurality of eyes 36 may be secured to only one ring and in this manner also permit a plurality of airplanes to be flown at one time.

From the foregoing description, the construction and operation of the toy flight control apparatus forming the present invention is believed to be clearly apparent. However, since numerous modifications and changes will readily occur to those skilled in the art after a consideration of the foregoing specification taken in conjunction with the accompanying drawings, it is not desired to limit the invention to the exact construction shown and described. But, all suitable modifications may be resorted to falling within the scope of the appended claims.

Having described the invention, what is claimed as new is:

1. A toy for controlling the flight of a model airplane including a pylon, a ring concentrically surrounding said pylon and adapted to ride upwardly on said pylon in eccentric circles in response to the movement of a model airplane adapted for attachment thereto, means on the bottom of said pylon for securing the same to a supporting surface and means at the top of said pylon for limiting the upward movement of the ring thereon, said pylon being pyramidal in shape, the motion of said ring around the pylon forming progressively wider circles with respect to the pylon in its upward movement.

2. A toy for controlling the flight of a model airplane including a pylon, a ring concentrically surrounding said pylon and adapted to ride upwardly on said pylon in eccentric circles in response to the movement of a model airplane adapted for attachment thereto, said pylon being pyramidal in shape, the motion of said ring around the pylon forming progressively wider circles with respect to the pylon in its upward movement.

3. A toy for controlling the flight of a model airplane including a pylon, a ring concentrically

surrounding said pylon and adapted to ride upwardly on said pylon in eccentric circles in response to the movement of a model airplane adapted for attachment thereto, and means at the top of said pylon to limit the upward movement of the ring on the pylon, means on the bottom of said pylon for securing the same to a supporting surface and means at the top of said pylon for limiting the upward movement of the ring thereon, said pylon being pyramidal in shape, the motion of said ring around the pylon forming progressively wider circles with respect to the pylon in its upward movement.

4. A toy for controlling the flight of a model airplane including a pylon, a ring concentrically surrounding said pylon and adapted to ride upwardly on said pylon in eccentric circles in response to the movement of a model airplane adapted for attachment thereto, means on the bottom of said pylon for securing the same to a supporting surface and means at the top of said pylon for limiting the upward movement of the ring thereon, said means at the bottom of said pylon consisting of flat, horizontally extending tabs secured to the bottom of said pylon, said pylon being pyramidal in shape, the motion of said ring around the pylon forming progressively wider circles with respect to the pylon in its upward movement, said means at the top of said pylon consisting of a retaining disc constituting a cap for the pylon.

5. A toy for controlling the flight of a model airplane including a pylon, a ring concentrically surrounding said pylon and adapted to ride upwardly on said pylon in eccentric circles in response to the movement of a model airplane adapted for attachment thereto, and means at the top of said pylon to limit the upward movement of the ring on the pylon, said pylon being pyramidal in shape, the motion of said ring around the pylon forming progressively wider circles with respect to the pylon in its upward movement.

6. In the combination with a self-propelled miniature aircraft, a toy flight control apparatus comprising an upwardly tapered pylon, a ring surrounding said pylon and frictionally seated adjacent the lower end of the pylon, a member interconnecting the miniature aircraft and the ring whereby upon propulsion of the aircraft the ring rides up the pylon.

MELVIN H. FREEDMAN.
